UNITED STATES PATENT OFFICE.

FRANK KUSTERLEE, OF KENOSHA, WISCONSIN, ASSIGNOR TO THE SIMMONS MANUFACTURING COMPANY, OF KENOSHA, WISCONSIN, A CORPORATION OF WISCONSIN.

ASSEMBLING DEVICE.

1,279,365.

Specification of Letters Patent. Patented Sept. 17, 1918.

Application filed October 9, 1915. Serial No. 55,065.

To all whom it may concern:

Be it known that I, FRANK KUSTERLEE, a citizen of the United States, residing in the city of Kenosha, county of Kenosha, and 5 State of Wisconsin, have invented certain new and useful Improvements in Assembling Devices, of which the following is a specification.

My invention relates to improvements in 10 cotters and devices for applying same, and in certain of its features has many applications. The particular device, which will be illustrated and described in this specification as demonstrating a particular embodiment of 15 the invention, is a cotted which is used to connect the frenching or corner casting connection to a tubular metal bedstead and a device for quickly and efficiently applying or inserting the cotted without injuring the bedstead 20 parts.

In the drawings which accompany this application—

Figure 1 is a longitudinal section through a tube of a metal bedstead frame showing the 25 cotted and the applying device inserted in the tube before the frenching is connected;

Fig. 2 is also a longitudinal section through the tube shown in Fig. 1, and taken at right-angles to Fig. 1, showing the tube dropped 30 down over the frenching;

Fig. 3 is an end view of a crank for drawing up the cotted;

Fig. 4 is a section taken on the line 4—4 of 35 Fig. 2;

Fig. 5 is a section taken on the line 5—5 of Fig. 2;

Fig. 6 is a perspective view of the cotted; and

Fig. 7 is a section of the completed connection between the frenching and the tube.

Metal bedsteads are usually constructed with tubular post members at each corner of the bedstead, the end frames of which are joined by means of side rails connected 45 to the corner posts by means of interlocking cast-iron blocks secured, respectively, to the ends of the side rails and the sides of the posts. The female cast-iron block or corner fastening is usually secured to the post, and 50 in the trade is known as a frenching. In the heavier types of bedstead frames, the corner fastenings or frenchings are usually cast around or in interlocking engagement with the hollow post members, so that no 55 other internal or extraneous connection is required. However, in certain classes of

bedsteads, such as those having the posts constructed entirely of brass, with a brass sheath, or of extremely thin steel, it is not practical to cast the frenching in interlocking engagement with the post on account of the danger of injuring the surface of the tube. For other reasons, it is frequently not desirable to cast the frenching directly upon the post and some other means must be employed to securely mount the frenching upon the side of the tube, an efficient frenching connection being illustrated in the drawings hereto annexed.

Referring to the drawings in Fig. 4, 10 70 represents the hollow post member to which the frenching 11 may be connected by means of the cotted 12 lying on the inside of the post and engaging a staple 13 carried by the frenching 11 and projecting through an 75 aperture 14 in the side of the post. In the drawings, the cotted 12 is not shown actually in engagement with the staple, but in readiness to be drawn into position by means of the cotted-applying device. In the particular 80 combination of post and frenching and the connection therefor which is illustrated, the post 10 is made of comparatively thin sheet metal, and distortion thereof by the use of the staple and cotted is prevented by inserting between the inner wall of the tube and the cotted a curved plate 15, which is also 85 perforated to admit the staple 13. The side of the frenching which engages the outer wall of the post is curved to correspond with the 90 curvature of the post, and, for convenience, the staple 13 is fixed in the frenching by casting the latter directly upon the legs 16 of said staple, which is preferably made of 95 tough steel or similar metal.

Owing to the competition in the bedstead business, it has been the custom heretofore to make the wedges or cotters 12 of malleable cast-iron and drive the same into the staple by means of a heavy rod or other device inserted into the tube from the open foot end thereof. The use of malleable cotters or wedges has been subject to many disadvantages, among which are the high cost of the wedge, the inaccuracy in the dimensions 100 of the same, which result in rejection of a large proportion, due to poor fit, and particularly the lack of resiliency of the wedges or cotters which often were found to rattle loose and drop out of the staple during shipment or after the bedsteads had been placed 105 in service.

My improved cotter has eliminated all of the above stated disadvantages of the old-fashioned malleable cast-iron cotter and in addition possesses other advantages, as will 5 hereinafter appear. The cotter is constructed from a tapered, elongated blank of sheet steel, or other metal, folded up in the shape illustrated in Fig. 6. Referring to said figure, it will be seen that at the 10 small end 17 of the cotter the side folds of the same are not as wide as at the rear end 18, and, in addition, the folds are splayed apart at the rear end 18, as shown more clearly in Fig. 5; while at the front 15 end 17 the said folds are comparatively close together and substantially parallel. For convenience in inserting the cotter into the staple upon its entering movement, the side folds at the small or front end 17 of 20 the cotter are cut away or beveled off, as shown at 19 in Fig. 6. The spacing of the side folds of the cotter at the front end 17 thereof is such that the said front end will enter rather freely into the space between 25 the legs of the staple 13, but as the cotter is driven or forced into the staple, the rear end of the cotter, which is thicker across the folds than the space between the legs of the staple, will be compressed tightly, the 30 folds thus being forced together and caused to press outwardly with great force against the legs of the staple. The cotter is driven or forced into the staple until the cotter enters the staple to a position where the 35 tapered character of the cotter with respect to its width across the flats of the folds, causes the curve of the fold to be pressed tightly into the inner curve of the staple, and the longitudinal edges of the 40 sides of the cotter to engage the inner side of the plate 15 with great force. The position of the parts when the staple has been driven into its final position in the connection is illustrated in Fig. 7.

45 My improved coppers or wedges may be constructed of comparatively cheap flat steel or iron, and, since they are made by means of punches and dies, they are all substantially alike in their dimensions and fit perfectly. Although they may be manufactured extremely cheaply, they are nevertheless extremely efficient inasmuch as the 50 resiliency of the wedges makes it impossible for them to become loosened up, due to shaking or vibration during shipment or while in service. Although I have since my 55 invention applied coppers of this type to many thousands of frenching connections, I have never heard of a copper loosening up or 60 falling out after it has once been securely driven or forced into place. The combination of the copper and staple in the frenching connection herein shown is particularly 65 efficient for the reason that in folding the copper, the outer curve of the metal of the

fold is the same as the natural inner curve of the staple, which is also formed up by means of a punch and die from tough strip metal, as before stated; hence, it is not necessary to construct the staple with difficult angles or troublesome sharp bends, as would be the case if a copper rectangular in section were used.

When I first invented my improved copper, I applied the same by driving it into 75 the staple from the open foot end of the bedpost. This method of applying the copper I found to be fairly satisfactory for bedstead frames constructed of comparatively heavy gage tubing, but where the 80 tubing of the bedpost is comparatively thin, there is a tendency to bend or distort the post when the wedge is pounded into the staple, both on account of the sudden sharp blow of the driving instrument, and also on 85 account of the fact that usually an excessive amount of force is applied. For this reason, I have devised the device described herein which enables me to gradually draw the copper into the staple without the exercise of excessive force or blows which might injure the bedpost.

The device in its preferred form comprises a carrier 20 which supports the key or copper 12 and is introduced into the post 95 on the end of a rod 21, the outer end of which is threaded to accommodate a nut 22. The carrier 20 on its lower side is curved to correspond substantially with the curvature of the interior of the post 10, and is formed with a central slot 23 extending substantially the greater part of the length of the carrier. In the inner end of the said slot 23 I secure, by means of a screw 24, a steel insert 25 which, at its outer end is 105 formed with a tongue 26 of suitable shape to fit within the rear end 18 of the wedge or copper 12 which is thus supported longitudinally of and in the slot 23 of the carrier. The smaller end 17 of the copper 12 110 rests upon the curved plate 15, which is also introduced into the tube by means of the device and is carried by a small curved plate 27 which is screwed to the under side of the outer end of the carrier and forms 115 a supporting shelf for said plate. The carrier is cut away on its under side for the reception of the plate 15 which is positioned longitudinally by the shoulder 28 formed by said cutting away of the under side of the 120 carrier 20. The key 12 is also maintained in its proper position in the slot 23 by means of a flat steel spring 29 which is screwed upon the top of the insert 25.

In practice, the tubes or posts 10 are all 125 cut to the same length and the apertures 14 in the posts are all punched at the same distance from the ends of the tubes. On the rod 21, between the nut 22 and the carrier, I mount a loosely fitting apertured collar 30, 130

slightly larger in diameter than the end of the tube, and having a tapered neck 31 which readily enters the bore of the post. I also arrange upon the outer end of the threaded rod 21 a pair of threaded lock-nuts or collars 32 and 33 which are set at the proper distance from the carrier so that when the nut 22 is screwed completely back and engages the collar 32, and the neck 31 enters the end of the tube with the outer face of the part 30 engaging the nut 22, the hole 34 in the plate 15 will be in register with the hole in the post.

In using the device, I prefer to secure the 15 frenching 11 in a suitable support, with the staple 13 projecting upwardly, and lay the bedpost in the proper position so that the staple enters the hole. I then, without disturbing the position of the post as a whole, 20 elevate the outer end thereof sufficiently to permit the introduction of the carrier which supports the cotter on the plate 15, as shown in Fig. 1. The end of the tube is then lowered so that the staple enters the hole 25 in the post and also the hole in the plate 15. The operator then, by hand, gives a quick pull upon the projecting end of the device so as to make the small end of the wedge 12 enter the staple. By the same movement, 30 the supporting plate 27 is pulled from under the curved plate 15, which is thus forced into engagement with the inner wall of the tube. The wedge 12 is then forcibly drawn into 35 the staple the additional distance necessary to make a tight connection, by means of a connecting handle 35 applied to the nut 22. In order to save time, it is frequently desirable, before applying the crank, to screw up the nut 22 by the fingers as far as possible. After the crank 35 has been operated 40 to the limit and forced the cotter 12 into its final position, the nut 22 is slackened off until it again occupies the position shown in Fig. 1, whereupon the carrier, by means of a sharp blow on the projecting end of the 45 screw, is disengaged from the cotter and may then be removed from the tube.

This method of inserting the cotters into the frenching connections possesses many 50 advantages over the old way of pounding them in by means of a heavy rod or other instrument introduced into the open end of the post. In the first place, it enables the cotter to be inserted with a substantially uniform amount of force; and in the second place, the pressure necessary to force the cotter into the staple is not suddenly applied, consequently there is no danger of breaking the staple or of distorting the 55 tube, as in the case where the cotter receives a sudden heavy blow. Another advantage is that in case occasion arises, the connection 60 may be disassembled with comparatively

little trouble by applying a punch to the small end 17 of the cotter and driving it out 65 of the staple; whereas, in the old method, where the cotters are inserted from the outer end of the tube instead of from the inner end, it is extremely difficult to obtain secure enough grip on the large end of the cotter 70 to enable it to be pulled out of the staple.

In this specification I have described the application of my invention to a frenching connection for a round tube, but it should be understood that the invention has many applications and may be used for various purposes in the same or a modified form. The scope of my invention, therefore, is not intended to be limited, except as specified in the appended claims.

I claim:

1. In a device for applying a longitudinal key and a washer to a longitudinal seat in the interior of a hollow post, the combination of a carrier insertible into the open end of said post for supporting said key to locate the same in entering position, washer holding means at the outer end of said carrier and means connected to said carrier and bearing against the open end of said post for forcing said key into its desired position over said washer.

2. In a device of the class described the combination of a rod having a threaded end arranged to project from the end of a hollow post means including a nut and a part bearing against the end of said post for pulling said rod outwardly of said post and a carrier carried by the inner end of said rod and provided with key-holding means at its inner end and washer supporting means at its outer ends, said means being suitably spaced whereby the outer end of said key rests upon the inner end of said washer.

3. In a device of the class described the combination of a rod having a threaded end arranged to project out of a hollow post, a washer surrounding said threaded end and adapted to bear against the end of said post, a nut threaded on said outer rod externally of said washer, a carrier secured to the inner end of said rod and offset from the axis thereof, washer-holding means at the inner end of said carrier, and key-supporting means at the outer end of said carrier, said means being suitably spaced whereby the outer end of said key rests upon and is supported by the inner end of said washer, said carrier being suitably slotted intermediate said means to permit relative movement of a part extending through said washer.

FRANK KUSTERLEE.
